ATTACHMENT FOR ROTARY IMPACT TOOLS

Marston H. Boden, Weston, Mass.

Application May 20, 1949, Serial No. 94,406

17 Claims. (Cl. 125—33)

1

The present invention relates generally to attachments for rotary impact tools, and more particularly to attachments for such tools by which their impacts, which are directed in a rotary manner so as to apply force torsionally, are translated into impacts directed substantially linearly.

Such impact tools are well known and in general use, and as they are adapted to apply intermittent impacts torsionally at the rate of 1700-1900 or more per minute, they are much employed, when fitted with attachments as may be needed, for such operations as tapping, drilling, reaming, nut running, boring, screw driving, stud removing, hole sawing, wire brushing, buffing, and the like. Rotary impact tools themselves as a class are characterized by having as fundamentals of structure: (a) a motor which may be electric or air driven; (b) a reciprocable hammer member which is rotatable from the motor; (c) an anvil member which is normally engaged by the hammer so as to be rotatable thereby but from which the hammer is disengageable as the result of movement away from the anvil; (d) resilient means normally but releasably maintaining the hammer and anvil in operative engagement; and (e) structure cooperating with the hammer and functioning as a clutch so that upon a stalling of the anvil, as when a nut is fully run on, to give but one example here, the hammer is automatically withdrawn from the anvil without any interruption in motor operation. The free end of the anvil is usually squared or otherwise shaped to fit as a driver into a work-engaging tool piece or to receive a socket or chuck for holding such a tool piece.

It is to be noted that the various operations listed above for which rotary impact tools are employed all involve rotation of the work-engaging tool piece itself and of its socket, chuck, or the like if used. In view of this, it will therefore be seen that such impact tools are unsuited for those many operations which are best or are necessarily performed by impacts directed substantially linearly. For such operations the power source is a reciprocating impact tool or power hammer, one directing its succession of impacts in substantially a straight line as opposed to torsionally, and examples of operations which require such linearly directed impacts are rivet setting, beading, drilling with star drills or other drills operated by blows struck along a longitudinal axis, chipping, tamping, stone dressing as with a bush hammer, surfacing, chiseling, stripping, cutting, scaling, seaming, channeling, calking, plugging, pointing, hammering, edging, gouging, slotting, and the like.

The capabilities of rotary impact tools and reciprocating impact tools or power hammers being thus largely mutually exclusive, it is the principal object of the present invention to provide an at-

2

achment by which a rotary impact tool may be used as the power source for those operations for which reciprocating impact tools are now designed as the power source. Since both types of impact tools are relatively expensive the use of the attachment constituting the present invention means the elimination of a material item of tool cost, a factor of importance both in small shops, where economy requires that one power tool be used for as many operations as possible, and also in large shops where many such power tools may be employed.

It is a further object of the present invention to provide an attachment for rotary impact tools by which certain operational economies may be effected as the result of substituting linearly directed impacts for torsionally applied impacts. To give one specific example here, when a rotary impact tool of $\frac{1}{2}$ " drive and $\frac{3}{8}$ " capacity is used with a rotary drill for drilling holes in masonry, concrete, or brick, a hole diameter of $\frac{3}{8}$ " is the maximum practicable, but at even smaller diameters the hole to be drilled may become glazed over so that the rotating drill cannot function or so that its progress is slowed up or stopped altogether. In addition, the performance of such drilling by rotary means requires that the operator himself supply the lineal pressure to effect penetration into the work, and this results in fatigue. Moreover, the drills themselves, by reason of the high resistance which such work offers, become quickly dulled and may be easily broken. It will therefore be appreciated that by using for such purposes a rock drill, which requires for its operation a succession of blows along its length, the difficulties presented by glazing are eliminated and those presented by dulling and breakage are minimized, and that by using with a rotary impact tool as the power means for such drilling an attachment which translates torsional force into blows directed substantially linearly, the fatigue on the operator is minimized since the attachment and the impact tool together act to cause the work penetration which the operator would otherwise have to effect by pressure exerted linearly by himself.

To the accomplishment of these objects and of others which will appear hereinafter, the various features of the present invention reside in constructions and formations all fully described in the following specification and then set forth in the appended claims the subject matters of which possess advantages which will be readily apparent to those skilled in the art and in the use of rotary and reciprocating impact tools.

The various features of the present invention will be readily understood from reading this specification in connection with the accompanying drawing which illustrates the best physical

embodiments of the claimed invention at present known to the inventor and in which:

Fig. 1 is a detail view in sectional elevation of the forward portion of one type of rotary impact tool thousands of which are now in general use;

Fig. 2 is a view in plan of one embodiment of the present invention as used with a star drill;

Fig. 3 is a view in elevation of the embodiment shown in Fig. 2, the body passage receiving the square driver of a rotary impact tool;

Fig. 4 is a view in end elevation of the Figs. 2-3 embodiment;

Fig. 5 is a view in elevation of an alternative embodiment of the present invention, in association with a socket used with the driver of a rotary impact tool;

Fig. 6 is a view in end elevation of the Fig. 5 embodiment;

Fig. 7 is a detail view in elevation, partially in section, showing an alternative socket used in an embodiment which may be otherwise like the Figs. 2-4 embodiment;

Fig. 8 is a detail view in elevation, partially in section, showing an alternative socket used in an embodiment which may be otherwise like the Figs. 5-6 embodiment;

Fig. 9 is a view in elevation of a modification of the Figs. 2-4 embodiment, characterized by the absence of the grip extension shown in Figs. 2 and 3.

Fig. 10 is a view in elevation, partially broken away, of an embodiment of the present invention provided with an angularly disposed extension; and

Fig. 11 is a view in elevation of an embodiment of the present invention corresponding to Fig. 10 but having a tool socket located in the angularly disposed extension.

Referring to the drawing, the rotary impact tool detailed in Fig. 1 is of the type adapted to be held in one hand by means of a pistol grip, is trigger-operated, and is provided with an electric motor and means for reversing the motor as circumstances of the work require. These elements are not shown because they are old and well known and form no part of the present invention. In the forward portion of the tool housing, indicated by the numeral 15, is a rotatably mounted frame 16 operatively connected to gearing (not shown), and mounted reciprocably on the frame 16 for rotation therewith is a hammer member 17 the forward end portions of which are shaped to engage corresponding portions on the rear of an anvil member 18 rotatably mounted in the forward portion of the housing 15. A spring 19 coiled about the frame 16 functions to maintain the hammer 17 and anvil 18 normally in engagement so that the former drives the latter, but the reciprocity of the hammer on the frame 16 and the surface formation of those portions of the hammer and anvil which engage each other are such that partial or absolute resistance to rotation exhibited by the anvil 18 results in the hammer 17 automatically moving rearwardly on the frame 16 (to the right, viewing Fig. 1) and riding off the anvil, this action being made possible by a clutch construction comprising cam balls 20 and cooperating grooves therefor forming part of the frame and hammer structure. With this arrangement, the motor and frame 16 rotate continuously even when the anvil 18 is stalled, and since the spring 19 tends to maintain the hammer and anvil normally in engagement, the hammer is repeatedly urged into engagement with even a stalled anvil.

As a result, the hammer delivers a succession of torsional impacts on the anvil at the rate of 1700-1900 or more per minute, even though rotation of the anvil under the force of such impacts is impossible. This rapid succession of impacts by the rotating hammer on a stalled anvil is the basis for the operation and functioning of the attachment constituting the present invention.

Further structure shown in Fig. 1 comprises the integral forward end member 21 of the anvil 18, which extends outwardly of the housing 15, is shown as square in cross section for illustrative purposes only, may be provided with a conventional spring-pressed plunger 22 for retaining a socket or tool piece, as is well understood, and is referred to as the driver 21 in the remainder of this specification. The details of rotary impact tool structure are illustrated in many patents and other printed publications, but for a few specific citations of such patents under which such tools are now made and marketed, reference is here made to the Pott patents, No. 2,012,916, granted August 27, 1935, and No. 2,049-273, granted July 28, 1936, to the Thomas patent, No. 2,463,656, granted March 8, 1949, and to the patents cited on the last page of said Thomas patent.

The attachment constituting the Figs. 2-4 embodiment of the present invention is provided with a rod-like body 23 which is preferably of integral construction and is shown as being a straight length which is circular in cross section, although it may have any suitable cross section desired. Adjacent one end of the body 23 is provided with a tapered passage 24 which may extend through the body transversely thereof, i. e., at substantially 90° to the longitudinal axis of the body, and functions as a holder or socket for receiving the tapered end 25 of the shank of a work-engaging tool piece herein illustrated merely for disclosure purposes as a star drill 26. Spaced from the socket 24 the body 23 is provided with a second passage 27 which also may extend through the body transversely thereof, i. e., at substantially 90° to its axis, but the axis of the passage 27 is itself at substantially 90° to the axis of the socket 24. The passage portion 27 is shown as shaped square in cross section merely for illustrative purposes, and is so shaped to function as a socket for receiving non-rotatably the square driver 21 of the rotary impact tool, as indicated in Fig. 3. With this construction the driver 21 and the passage portion 27 are coaxial when the former is inserted in the latter, and this coaxiality is at substantially 90° to the axis of the socket 24. Alternatively stated, the axis of the holder or socket 24 lies in a plane which the axis of the passage 27 intersects at substantially 90°.

Further structure of the Figs. 2-4 embodiment comprises the remainder of the body 23 which functions as an integral extension or grip 28 which is coaxial, if desired and as shown, with the body 23 and which an operator may grasp to support and steady the body and the star drill 26 held by the socket 24. The socket or holder 24 is thus located at one side of the driver passage portion 27 and the extension 28 is located at another side of the passage portion 27.

In using the Figs. 2-4 embodiment of the present invention, an operator may grasp the extension 28 in his right hand, for example, so as to hold it and the body 23 horizontal as indicated in Fig. 2 with the bit of the star drill 26

engaged with a stationary masonry or rock surface S. The rotary impact tool, set to rotate the frame 16 and the hammer 17 in a clockwise direction, is held in the operator's left hand with the driver 21 directed downwardly and inserted in the driver passage 27. With the impact tool so held, the axis of rotation of the driver 21 is at 90° to the longitudinal axis of the body 23, and with this arrangement it will be apparent that if the trigger of the impact tool be depressed, the tendency of the hammer 17 to rotate the anvil 18 clockwise will cause the driver 21 to tend to rotate the body 23, the star drill 26, and the extension 28 as a unit clockwise about the axis of the driver. But actual rotation in this manner does not take place because it cannot, for the engagement of the star drill with the stationary surface S makes such rotation impossible. The body 23, star drill 26, and extension 28 thus remain stationary, i. e., non-rotative, as it were, and as a consequence the hammer 17 rides upwardly off the anvil, but the action of the spring 19 in constantly urging the hammer back into driving engagement with the anvil causes the anvil to receive a series of torsionally directed hammer impacts in a rapid succession which is continued as long as the trigger of the impact tool remains depressed.

The torsional impacts applied to the anvil 18 by the rotating hammer 17 are transferred clockwise to the driver 21 because the driver is an integral part of the anvil, and as a consequence the driver applies torsional impacts clockwise to the body 23 because the driver is inserted in the body portion passage 27 which is shaped to receive the driver in non-rotative engagement. Since the body 23 cannot rotate, the force of these impacts is transferred by the body to the socketed end 25 of the star drill 26 and thence longitudinally of the star drill to its bit engaged with the work, and since the direction of rotation of the hammer 17 is clockwise, the transferred torsional impacts drive the star drill substantially axially toward, i. e., into, the work so that the surface S is subjected by the star drill to successive blows delivered with great rapidity and force in a substantially lineal manner. During the delivery of these impacts the star drill may be turned about its own axis, as is necessary in the use of such drills, by the operator simply swinging the extension 28 and body 23 small amounts about the star drill axis as a center, the impact tool itself being tilted during such swinging to maintain the axis of the driver 21 at substantially 90° to that of the body 23.

An alternate, and for some purposes more easily performed, manner of operating the Figs. 2-4 embodiment is to hold the body 23 and extension 28 vertically in parallelism with the surface S, the holder 24 and star drill 26 being above and the extension 28 being below. The right hand of the operator may again be used for this purpose and for holding the star drill against the surface S, but the impact tool, this time set to cause rotation of the frame 16 and the hammer 17 in a counter-clockwise direction, would be held horizontally by the left hand and the driver 21 would be inserted into the left end of the passage portion 27. Depression of the trigger of the impact tool would cause torsional impacts to be delivered by the hammer 17 in a counter-clockwise manner to the anvil 18, and these would be transferred by the driver 21 to the body 23 and by the body to the star drill 26 substantially axially thereof to effect repeated blows of the

star drill on the surface S in a manner corresponding to that set forth in the immediately preceding paragraph. Should the body 23 and extension 28 be held vertically by the left hand and the impact tool be held horizontally by the right, the latter would, of course, be set to operate in a clockwise manner because the impact tool would itself be located to the right of the body 23 and extension 28. But whichever hand would be used to grasp the extension, it will be seen that the extension may easily be swung small amounts, and the impact tool correspondingly tilted from the horizontal, to turn the star drill 26 about its own axis during repeated impacts thereon while in engagement with the work.

Since either of the above modes of operation tends to cause the star drill shank end 25 to be forced tightly into the socket 24, it may be noted at this point that by disengaging the star drill 26 from the surface S while maintaining a grip on the extension 28 or the body 23 and by then reversing the direction of rotation of the motor to reverse the direction of impact transference to the body 23 by the driver 21, the resulting vibration tends to loosen the shank end 25 in the socket 24 so that the star drill falls out or may be easily removed.

It is realized that since the impacts delivered by the driver 21 to the body 23 are torsional impacts, their force is not directed by the body along the exact longitudinal axis of the star drill 26, as is the case by a blow properly delivered on the end of a star drill in the usual manner by a sledge. But the body 23 necessarily causes the impacts to be delivered in close approximation to the exact axiality of the star drill, and as their force is directed longitudinally of the shank of the star drill, the torsional impacts of the driver 21 are translated by the body into impacts which are substantially lineal. A factor here in the practical translation of torsion to lineality is the fact that the body portion passage 27 is spaced from the socket 24, i. e., the latter is located at one side of the former. If the passage portion 27 were located directly over the socket 24, for example, it will be seen from Fig. 2 that the star drill as a whole would become a radius the center for swinging of which would be its socketed end 25, and as a consequence there would be a strong tendency for the opposite or bit end of the star drill to swing arcuately away from the surface S as the immediate result of each impact of the hammer 17 upon the anvil 18. This would be the case because the driver 21 engages the passage portion 27 on at least two opposed areas, and the impact force which is delivered to the body 23 by one driver face or portion thereof and which would tend to cause the star drill to bite into the surface S would be equalled, or substantially equalled, by the impact force which is delivered to the body 23 by another driver face or portion thereof and which would tend to cause the star drill as a whole to swing arcuately away from the surface S about the axis of the driver 21. Under such conditions the operator would have to use maximum effort, for in addition to grasping the extension 28 to support the body 23 and star drill while maintaining the latter engaged with the surface S in counter-action to the natural tendency of the star drill to bounce directly back from the work under the influence of the impacts delivered on its socketed end, the operator would also have to grasp the extension 28 so as to counteract the tendency of the star

drill as a whole to swing arcuately away from the surface S.

By increasing the length of the radius about which the star drill 26 tends to swing arcuately, the force of this tendency to swing away from the surface S may be reduced and minimized and simultaneously the force of the tendency of the star drill to bite into the surface S may be increased, and this is accomplished by spacing the passage portion 27 from the holder or socket 24, i. e., by locating the holder 24 at one side of the passage portion 27. Taking Fig. 2 as merely one illustrative example of such spacing, it will be seen that the distance between the axis of the passage portion 27 and the center of the front face of the bit of the star drill 26 is greater than the length of the star drill itself. If an imaginary line be considered as drawn between these two points, it will be seen that the angle between such a line and the longitudinal axis of the body 23 is materially less than 90°, and from this it follows that if such imaginary line were swung about the axis of the passage portion 27 to a position of being at 90° to the surface S, the forward end of the imaginary line would be located behind and beyond the surface S and not at it, as is the case of the front face of the bit of the star drill 26 in Fig. 2. As a consequence, a portion of the force which would tend to cause the star drill to swing arcuately away from the surface S were the passage portion 27 located directly over the holder or socket 24 is, in the Fig. 2 spacing illustration, utilized as an additional force increment tending to urge the star drill to bite into the surface S. The existence of spacing between the socket or holder 24 and the passage portion 27 thus reduces and minimizes the tendency of the star drill to swing arcuately away from the work and as a consequence reduces and minimizes the effort required of the operator to counteract such tendency.

From these considerations it follows that the greater the distance between the holder or socket 24 and the passage portion 27, i. e., the greater the distance between the center of the front face of the star drill or other tool piece mounted in the holder 24 and the axis of the passage portion 27, the less will be the tendency of the tool piece to swing away arcuately from the work and the greater will be its tendency to bite into the work. As a theoretical matter this spacing may thus be very large indeed, but considerations of weight, size, and ease of handling of embodiments of the present invention place practical limitations on the above distance or spacing possibilities. Where an impact tool has a driver of less than $\frac{1}{2}$ " square size, one practical distance between the holder or socket 24 and passage portion 27 axes can be as little as 2" or may be larger. Where an impact tool driver is of $\frac{1}{2}$ " square size, a distance of 3" between these axes is more satisfactory, and where the size of the driver is greater than $\frac{1}{2}$ ", a spacing of more than 3" between these axes is desirably employed. It should be understood, however, that these spacing distances are not critical for any given embodiment, but it is desirable that the spacing not be so great that when in use a body 23 will exhibit appreciable flexing between these axes under the force of the impacts from the driver 21. The axes spacing shown in the various Figures is thus to be considered as exemplary only.

The structure shown in Figs. 2-4 is designed to receive the driver member 21 directly, but since manufacturers of these impact tools supply re-

movable sockets for the drivers in the interest of greater adaptability of the tools, an alternative embodiment of the present invention, in all other respects identical with the structure shown in Figs. 2-4, may be provided with a body 29 (Figs. 5-6) having an integral boss or fixed projection portion 30 as a substitute for and in the location of the Figs. 2-4 passage portion 27. The portion 30 is shown as shaped hexagonally in cross section merely for illustrative purposes, and is so shaped to receive non-rotatively the hex end of an adapter in the form of a socket member 31 of conventional construction, the other end of which is squared to receive the driver 21, as illustrated in Fig. 5. Since the projection portion 30 serves the same function for the socket member 31 as the body portion passage 27 serves for the driver member 21, the axis of the projection 30 transversely of the body 29 is at substantially 90° to the axis of the holder or socket 24, as indicated best in Fig. 6, i. e., the axis of the transverse extension 30 intersects at substantially 90° a plane in which the axis of the holder 24 lies. Impacts delivered torsionally to the driver 21 are transferred to the socket member 31 and so to the projection portion 30, by which they are in turn transferred to the body 29 and substantially linearly to the star drill or other tool piece mounted in the holder 24 in a manner which will be readily understood from the above considerations about the Figs. 2-4 embodiment.

The sockets or holders 24 in the Figs. 2-6 embodiments are shown as tapered and as extending through the bodies 23 and 29 merely for illustrative purposes, but it is not necessary that they extend all the way through in either case or that they be tapered. Tool pieces for performing operations such as those listed in the last sentence of the third paragraph of this specification are provided with straight or cylindrical shanks as well as with tapered ones, and for such tool pieces bodies 23A (Fig. 7) and 29A (Fig. 8) may be employed which in all other respects are identical with the embodiments of the present invention shown in Figs. 2-6. Instead of a tapered socket 24, however, each of these bodies 23A and 29A is provided with a blind end passage 32 which has the same location as a holder or socket 24, has an axis at substantially 90° to that of the passage portion 27 or projection portion 30 as well as to the longitudinal axis of its body 23A or 29A, respectively, as is the case of the socket 24, and functions as a holder for the end of the cylindrical shank 33 of a suitable work-engaging tool piece. Should the shanks of given tool pieces be other than circular in cross section, the blind end passages 32 may, of course, be correspondingly shaped. The Figs. 7-8 embodiments of the present invention thus function for tool pieces having straight shanks in the same manner as the Figs. 2-6 embodiments function for tool pieces having tapered shanks, and the Figs. 7-8 embodiments are handled and employed as above stated for Figs. 2-6.

In Fig. 9 there is shown an embodiment of the present invention characterized by having a body 23B from which the extension 28 shown in Figs. 2, 3, and 5 is omitted. Since the Fig. 9 embodiment is provided with the above-described holder or socket 24 and passage portion 27, it will be apparent that impacts delivered torsionally to the driver 21 by the impact tool are translated into substantially linear impacts upon the end of a star drill, for example, used with the body 23B, all in the manner described above, but that since the

extension 28 is omitted, the body 23B and tool piece held thereby must be supported differently than described above. This is accomplished by the operator supporting the impact tool in whichever hand may be convenient and then grasping with his other hand the portion of the body 23B which lies forwardly of the tool piece socketed in the holder 24. The grasping hand will be located at the base of the tool piece so that its tendency to bounce back from the work axially under the influence of the impacts delivered by the driver 21 may be easily counteracted by the operator. It will be understood, of course, that if desired there may be provided a body which is otherwise identical with the body 23B shown in Fig. 9 but having the Figs. 5-6 projection portion 30 substituted for the passage portion 27 and/or having the blind end passages 32 of Figs. 7-8 substituted for the holder or socket 24.

In using the above-described embodiments of the present invention and the modifications suggested, it will be apparent that if the trigger of the impact tool is never depressed until the body extension or body is steadied by the operator there will be no danger of the embodiments and tool pieces held thereby being spun around in the air, i. e., out of engagement with a surface or where they might endanger the operator by striking him. To provide a safety feature, however, which will prevent such spinning in the event of premature or accidental trigger depression, an embodiment of the present invention such as shown in Fig. 10 may be provided, having a body 23C which in all other respects may be identical with the body 23 in Figs. 2-4 but which has a two-part integral extension, one part 34 of which is coaxial with the body in the manner of the extension 28 in Figs. 2, 3, and 5 and the other part 35 of which extends from the part 34 as an integral arm shown as bent upwardly at substantially 90° to the part 34. The length of the extension part 34 is such that the distance between the axis of the holder or socket 24 and the extension arm 35 is slightly greater than one half the width of the housing 15 of the impact tool, so that with the impact tool driver 21 inserted in the passage portion 27, the housing 15 will clear the arm 35 and be parallel therewith. The length of the arm 35 is preferably such as to at least reach the forward portion of the pistol grip of the impact tool, and may be longer. With this construction, rotation of the body 23C and extension parts 34 and 35 as a unit upon accidental depression of the tool trigger results in movement through an arc of less than 360° before the arm part 35 strikes the pistol grip and is stopped, and there is no danger of the Fig. 10 embodiment and tool piece mounted thereon striking the operator and causing injury. In using the Fig. 10 embodiment, the operator would normally have the body 23C located vertically and would steady and support the embodiment by pushing on the portion of the body lying forwardly of the holder 24, in the same manner as described above for the embodiment shown in Fig. 9, and in this connection it is to be noted that since the operator would support the impact tool horizontally with the driver 21 inserted in the passage portion 27, the driver itself would furnish part of the support for the weight of the extension portions 34 and 35.

Instead of having an embodiment characterized by a safety arm extension located on the right, as shown in Fig. 10, there may be provided an embodiment in which the safety arm extension is on the left and in which the tool piece holder it-

self is located. Such an embodiment is shown in Fig. 11, and is provided with a body 36 corresponding to the body 23C of Fig. 10 in that it has at one end the transverse passage portion 27 for receiving the driver 21 as above described, but rising at substantially 90° from the other end is an extension arm 37, corresponding to the extension part 35 in Fig. 10 in length and function, and at the upper end of the extension 37 a tool piece holder is located, shown illustratively as the socket 24. The length of the body 36 is such that the distance between the passage portion 27 and the extension 37 is slightly greater than one half the width of the impact tool housing 15, and with this construction it will be seen that should the trigger be depressed accidentally when the tool piece is not engaged with the work, the extension 37 will strike the pistol grip in less than 360° of turning and will be stopped. The axis of the holder or socket 24 is at substantially 90° to the longitudinal axis of the extension 37 and of the body 36, and is also at substantially 90° to the axis of the passage portion 27. Torsional impacts delivered by the driver 21 are thus transferred to the body 26 and by it to the extension 37, so that the force of these impacts is directed substantially linearly longitudinally of the tool piece mounted in the holder or socket 24. In using the Fig. 11 embodiment, the operator would push rearwardly on, i. e., would grasp, the portion of the extension 37 which lies forwardly of the holder or socket 24, and if the extension 37 be positioned vertically in use it would be supported by the operator's grasping hand, for the impact tool would be vertical, but if the extension 37 is positioned horizontally, it would be supported in part by the driver 21 because the impact tool would also be held horizontally.

It will be appreciated that the holder or socket 24 and the passage portion 27 have been shown in Figs. 10 and 11 merely for illustrative purposes, and that these embodiments may alternatively be provided with the projection portion 30 of Figs. 5, 6, and 8 and/or with the blind end passage 32 of Figs. 7 and 8. It will also be appreciated that while the Fig. 10 embodiment may be considered as being right handed, a corresponding structure may be made left handed, and that the opposite is true of the Fig. 11 embodiment.

Embodiments of the present invention may be made of any material suitable for their purpose. It is preferred, however, that they be made of forged steel, suitably heat treated for strength and to withstand shock.

What is claimed as new is:

1. For use with a device adapted to translate continuous rotary movement into intermittent torsional impacts and provided with a member which is rotatable about an axis to deliver such impacts and which forms part of the device: an attachment comprising a rod-like body having a portion shaped to receive said device member non-rotatively so that the impacts of the member may be delivered to the body, said body also having a holder which is an integral part of the body and is located at one side of said shaped portion for receiving a tool piece adapted to act on the work under the influence of said impacts.

2. For use with a device adapted to translate continuous rotary movement into intermittent torsional impacts and provided with a member which is rotatable about an axis to deliver such impacts and which forms part of the device: an attachment comprising a rod-like body having a portion shaped to receive said device member

non-rotatively so that the impacts of the member may be delivered to the body; said body also having a holder which is an integral part of the body and is located at one side of said shaped portion for receiving a tool piece adapted to act along its longitudinal axis on the work under the influence of said impacts, said holder being so located with respect to said shaped portion that the axis of said tool piece is angularly disposed to the axis of said device member when the member is received by said shaped portion.

3. Structure such as set forth in claim 2 characterized by the fact that the shaped portion is a socket extending transversely of the body.

4. Structure such as set forth in claim 2 characterized by the fact that the shaped portion is a fixed projection extending from said body transversely of its axis.

5. For use with a device adapted to translate continuous rotary movement into intermittent torsional impacts and provided with a member which is rotatable about an axis to deliver such impacts and which forms part of the device: an attachment comprising a rod-like body having a portion shaped to receive said device member non-rotatively so that the impacts of the member may be delivered to the body; said body also having a holder which is an integral part of the body and is located at one side of said shaped portion for receiving a tool piece adapted to act along its longitudinal axis on the work under the influence of said impacts, said holder being so located with respect to said shaped portion that the axis of said tool piece is angularly disposed to the axis of said device member when the member is received by said shaped portion; said body also having a portion located generally at another side of said shaped portion and functioning as an extension of said body for gripping by the user.

6. For use with a device adapted to translate continuous rotary movement into intermittent torsional impacts and provided with a member which is rotatable about an axis to deliver such impacts and which forms part of the device: an attachment comprising a rod-like body having a portion shaped to receive said device member non-rotatively, said shaped portion having an axis which is angularly disposed to the longitudinal axis of the body so that the impacts of said device member when it is received by said shaped portion are delivered to the body at an angle to its longitudinal axis; said body also having a holder which is an integral part of the body and is located at one side of said shaped portion for receiving a tool piece adapted to act along its longitudinal axis on the work under the influence of said impacts, said holder having an axis which is angularly disposed to the longitudinal axis of the body and to the axis of said shaped portion.

7. Structure such as set forth in claim 6 characterized by the fact that the shaped portion is a socket extending transversely of the body.

8. Structure such as set forth in claim 6 characterized by the fact that the shaped portion is a fixed projection extending from said body transversely of its longitudinal axis.

9. For use with a device adapted to translate continuous rotary movement into intermittent torsional impacts and provided with a member which is rotatable about an axis to deliver such impacts and which forms part of the device: an attachment comprising a rod-like body having a portion shaped to receive said device member non-rotatively, said shaped portion having an

axis which is angularly disposed to the longitudinal axis of the body so that the impacts of said device member when it is received by said shaped portion are delivered to the body at an angle to its longitudinal axis; said body also having a holder which is an integral part of the body and is located at one side of said shaped portion for receiving a tool piece adapted to act along its longitudinal axis on the work under the influence of said impacts, said holder having an axis which is angularly disposed to the longitudinal axis of the body and to the axis of said shaped portion; said body also having a portion located generally at another side of said shaped portion and functioning as an extension of said body for gripping by the user.

10. For use with a device adapted to translate continuous rotary movement into intermittent torsional impacts and provided with a member which is rotatable about an axis to deliver such impacts and which forms part of the device: an attachment comprising a rod-like body having a portion shaped to receive said device member non-rotatively, said shaped portion having an axis which is at substantially 90° to the longitudinal axis of the body so that the impacts of said device member when it is received by said shaped portion are delivered to the body angularly to its longitudinal axis; said body also having a holder which is an integral part of the body and is located at one side of said shaped portion for receiving a tool piece adapted to act along its longitudinal axis on the work under the influence of said impacts, said holder having an axis which is angularly disposed to the longitudinal axis of said body and which lies in a plane which the axis of said shaped portion intersects at substantially 90°.

11. Structure such as set forth in claim 10 characterized by the fact that the shaped portion is a socket extending transversely of the body.

12. Structure such as set forth in claim 10 characterized by the fact that the shaped portion is a fixed projection extending from said body transversely of its longitudinal axis.

13. For use with a device adapted to translate continuous rotary movement into intermittent torsional impacts and provided with a member which is rotatable about an axis to deliver such impacts and which forms part of the device: an attachment comprising a rod-like body having a portion shaped to receive said device member non-rotatively, said shaped portion having an axis which is at substantially 90° to the longitudinal axis of the body so that the impacts of said device member when it is received by said shaped portion are delivered to the body angularly to its longitudinal axis; said body also having a holder which is an integral part of the body and is located at one side of said shaped portion for receiving a tool piece adapted to act along its longitudinal axis on the work under the influence of said impacts, said holder having an axis which is angularly disposed to the longitudinal axis of said body and which lies in a plane which the axis of said shaped portion intersects at substantially 90°; said body also having another portion located generally at another side of said shaped portion and functioning as an extension of said body for gripping by the user.

14. Structure such as set forth in claim 13 characterized by the fact that the shaped portion is a socket extending transversely of the body.

15. Structure such as set forth in claim 13

characterized by the fact that the shaped portion is a fixed projection extending from said body transversely of its longitudinal axis.

16. For use with a device adapted to translate continuous rotary movement into intermittent torsional impacts and provided with a member which is rotatable about an axis to deliver such impacts and which forms part of the device: an attachment comprising a rod-like body having a portion shaped to receive said device member non-rotatively so that the impacts of said member may be delivered to the body; said body also having a holder located at one side of said shaped portion for receiving a tool piece adapted to act on the work under the influence of said impacts; said body also having an extension located generally at another side of said shaped portion and angularly disposed to the axis of said body.

17. For use with a device adapted to translate continuous rotary movement into intermittent torsional impacts and provided with a member which is rotatable about an axis to deliver such impacts and which forms part of the device: an

attachment comprising a rod-like body having a portion shaped to receive said device member non-rotatably so that the impacts of said member may be delivered to the body; said body also having an extension located generally at one side of said shaped portion and angularly disposed to the axis of the body, said extension being provided with a holder for receiving a tool piece adapted to act on the work under the influence of said impacts.

Certificate of Correction

Patent No. 2,540,161

February 6, 1951

MARSTON H. BODEN

It is hereby certified that error appears in the printed specification of the above numbered patent requiring correction as follows:

Column 4, line 35, after "end" strike out "of"; column 6, line 70, after "counter" and before "action" strike out the hyphen; column 11, line 62, for the words "portion in" read *portion is*;

and that the said Letters Patent should be read as corrected above, so that the same may conform to the record of the case in the Patent Office.

Signed and sealed this 3rd day of April, A. D. 1951.

[SEAL]

THOMAS F. MURPHY,
Assistant Commissioner of Patents.
